UNITED STATES PATENT OFFICE

152,635

DESIGN FOR A KNEE PAD

Bert Mechur and Walter Riedler, New York, N. Y.

Application July 26, 1947, Serial No. 140,552

Term of patent 14 years

(Cl. D3—26)

To all whom it may concern:

Be it known that we, Bert Mechur and Walter Riedler respectively citizens of the United States, and residents respectively of the city, county, and State of New York, and the city of New York, county of the Bronx, State of New York, have invented a new, original, and ornamental Design for Knee Pad, of which the following is a specification, reference being had to the accompanying drawing, forming part thereof.

In which:

Fig. 1 is a plan view of a knee pad, embodying our new design.

Fig. 2 is a front elevation of the same.

Fig. 3 is a side elevation of the same.

We claim:

The ornamental design for a knee pad, as shown.

BERT MECHUR.
WALTER RIEDLER.
